US0D1080328S

(12) **United States Design Patent** (10) **Patent No.:** **US D1,080,328 S**
(45) **Date of Patent:** **** Jun. 24, 2025**

(54) **SOIL SAMPLER TOOL**

(71) Applicant: **Q.E.D. Environmental Systems, Inc.**,
Dexter, MI (US)

(72) Inventors: **Mark T. Weinberger**, Mounds View,
MN (US); **David B. Kaminski**,
Clayton, CA (US); **Daniel O. Hayes**,
Howell, MI (US); **Hunter C. Anstadt**,
Ann Arbor, MI (US)

(73) Assignee: **Q.E.D. ENVIRONMENTAL
SYSTEMS, INC.**, Dexter, MI (US)

(**) Term: **15 Years**

(21) Appl. No.: **29/854,656**

(22) Filed: **Sep. 27, 2022**

(51) LOC (15) Cl. **08-01**

(52) U.S. Cl.

USPC **D8/1**

(57) **CLAIM**

The ornamental design for a soil sampler tool as shown and described.

DESCRIPTION

FIG. 1 is a front elevational view of a soil sampler tool; FIG. 2 is a left side view of the soil sampler tool; FIG. 3 is a right side view of the soil sampler tool; FIG. 4 is a top plan view of the soil sampler tool; FIG. 5 is a bottom plan view of the soil sampler tool; FIG. 6 is a rear elevational view of the soil sampler tool; FIG. 7 is a first isometric view of the soil sampler tool; FIG. 8 is a second isometric view of the soil sampler tool; FIG. 9 is a third isometric view of the soil sampler tool; and, FIG. 10 is a fourth isometric view of the soil sampler tool. The broken lines in figures represent portions of the soil sampler tool and form no part of the claimed design.

1 Claim, 10 Drawing Sheets
